TABLE TOP

John W. Beiger, Ludington, Mich., assignor to The Carrom Company, Ludington, Mich.

Application July 24, 1933, Serial No. 681,848

1 Claim. (Cl. 311—106)

The main objects of this invention are:

First, to provide a table top construction especially adapted for card tables in which the necessity for a careful fitting of a top panel in the frame is eliminated.

Second, to provide such a structure in which a flexible covering is fastened on the table top in such a way that the edge of the covering is parallel with the edge of the table.

10 Third, to provide such a table in which the flexible covering is tucked or rolled into a groove or kerf in the table top in which the unsightly edges of the covering and any dirt falling into the groove are concealed.

15 Further objects and advantages pertaining to details and economics of construction and operation will appear from the description to follow.

A preferred embodiment of my invention is 20 illustrated in the accompanying drawing, in which:

Fig. 1 is a plan view of a table top embodying my invention having a portion of the flexible covering cut away to show the placing of the 25 panel.

Fig. 2 is a perspective sectional view taken on the line 2—2 of Fig. 1, showing the table top without the flexible covering.

Fig. 3 is a sectional view taken on the line 30 3—3 of Fig. 1.

1 is a table top frame having at its upper inner edge a rabbeted portion 2 adapted to receive a top panel 3. The frame may be of wood or any suitable material and the top panel may 35 likewise be wood or ply board or any suitable sheet material.

The panel 3 is disposed in the rabbeted groove 2 with its top lying flush with the top of the frame and having its outer edges 4 spaced from 40 the inner edges 5 of the frame. This eliminates any difficulty in fitting the top panel into the frame as it may be cut of such a size that it will fit readily within the rabbeted portion of the frame.

45 6 is a flexible cover which may be of leather

or leatherette or the like, which is disposed over the panel 3 and over a portion of the frame 1.

7 is a groove or kerf in the frame 1 into which the edges of the flexible covering 6 may be tucked by rolling or in any suitable manner well known to the art. This groove is parallel with the outer edge of the frame and slants from the top portion of the frame downwardly and outwardly. It will be seen that when the cover 6 is rolled in often the edge 8 is folded back on 10 itself which exposes the raw edge of the material. If the groove were not slanted, the edge of the material would be visible when viewed directly from above the groove. By slanting the groove, this is eliminated. This also conceals 15 any dirt that may lodge in the groove, giving a much neater appearance to the table after it has been used for some time.

The groove 7 is made parallel to the outer edge of and in the frame to improve the appearance 20 of the table. Quite often the frames of tables warp and if the groove is in the frame and parallel to the edge it creates an illusion of straightness even though the edge and the groove are both somewhat warped. Thus, the 25 table always has a neat appearance after considerable hard usage.

The edge 8 of the flexible covering 6 may be secured in the groove by gluing or in any other suitable way and the top panel 3 is preferably 30 held in its desired position by means of nails 9 extending through the panel and into the frame.

I have shown a preferred embodiment of my invention and wish to claim the same specifically and also broadly as pointed out in the appended 35 claim.

Having thus described my invention, what I claim as new and desire to secure by Letters Patent is:

The combination of a table top having a kerf 40 in the top surface thereof substantially parallel with the edge of said top and slanting downwardly and outwardly, and a flexible protective cover of leather or the like overlying said top and having its edges tucked into said kerf. 45

JOHN W. BEIGER.
